UNITED STATES PATENT OFFICE.

ALBERT G. GEISTERT, OF DETROIT, MICHIGAN, ASSIGNOR TO GENERAL MOTORS CORPORATION, OF DETROIT, MICHIGAN, A CORPORATION OF DELAWARE.

HORN-BUTTON CONTACT.

Application filed March 29, 1926. Serial No. 98,305.

This invention relates to a circuit controlling device. It is intended to be used in connection with a horn button assembly similar to that shown in patent to Lewellen 1,651,397 5 December 6, 1927 for "circuit controlling devices."

The particular feature to which this invention relates is a fixed contact within the steering column which cooperates with 10 a movable contact member reciprocating through and rotatable with the steering wheel hub.

It is an object of this invention to provide within the steering column a part including 15 the fixed contact so constructed as to permit the wire leading to the fixed contact to be positioned within the steering column instead of outside the column. In the drawing:

20 Figure 1 is a longitudinal vertical section through the steering column.

Figure 2 is a perspective of the bushing for the fixed contact member.

Referring by reference characters to the 25 drawing, numeral 1 represents the fixed steering column. Rotatable within the said steering column is the steering post 2. Secured to the upper end of the steering post and rotatable within the upper end of the 30 steering column is the hub of a steering wheel 3. The button for operating the horn is carried by the hub portion of the steering wheel. This button is represented by numeral 4. At its lower end it is outwardly flared, as at 5, 35 where it engages an inwardly directed portion 6 of housing 7 secured to the hub portion of the steering wheel by fastening means 8. Within the upper end of the steering post is recess 9 within which is placed a coil spring 40 10. This spring engages a plate 11 carried in the flared portion of the horn button 4. Depending from the plate 11 is a hair pin type of contact member 12.

It will be understood from the construction 45 described that the spring 10, by engagement with plate 11, normally holds the button 4 outwardly, the outward movement being limited by the engagement of parts 5 and 6.

50 When the button is in its outermost position, the inner ends of hair pin member 12 are out of contact with a fixed contact mem-

ber to be described below. When the button member 4 is pushed inwardly against the resistance of spring 10, the contact members 12 are brought into engagement with the 55 fixed contact member.

This invention is more particularly concerned with the structure relating to the attachment of the fixed contact member. In Figure 2 is seen a bushing 13 which is made 60 of insulating material, preferably of wood. This bushing is centrally apertured as at 14 for surrounding the steering post 2. The steering column has one or more indented portions 15 for engaging the tapered end of 65 bushing 13, as shown in Figure 1. The upper end of the bushing 13 is of reduced diameter and that part of the upper portion at the shoulder 15 is formed with a groove 16.

The fixed contact member 17 is in the form 70 of a shallow metal cup. It fits over the upper reduced portion of the bushing and one or more indentations of the flange of the cup, as at 18, engage the groove 16 to hold the fixed contact member in position. The bushing 75 is cut away on one side, as for example, by means of a groove 19, shown in Figure 2. Through this groove passes a wire 20 which enters the inner side of the fixed contact member to which it is soldered. The size of the 80 groove 19 is such as to permit the passage of the insulated wire and its connecting terminal. By means of this bushing it is possible to use a wire extending up through the inside of the steering column instead of 85 carrying the wire along the outside of the column.

The operation will be readily understood. The movable terminal is grounded through its connection with the button, the housing 90 and the steering wheel. When the button is depressed the movable contact members 12 engage the annular contact member 17 whatever be the position of the steering wheel. The contact is thus completed 95 through parts 12 and 17. When the pressure on button 4 is released the spring separates contact members 12 and 17.

I claim:

1. In an electric contact device for steering 100 columns, a fixed tubular column, an inner rotatable steering post, an annular insulating

bushing between said column and post, said bushing having its upper end of reduced dimensions, a metallic contact member secured to said reduced end whereby it is out of contact with said column, a second contact member movable into engagement with said first contact member.

2. The invention defined by claim 1, said bushing having an external groove whereby a wire may be connected to said first mentioned contact member and extend through said groove along the interior of said column. 10

In testimony whereof I affix my signature.

ALBERT G. GEISTERT.
